UNITED STATES PATENT OFFICE

SOLOMON WISE, OF CINCINNATI, OHIO

LOCK FOR SPARE WHEELS

Application filed March 8, 1928. Serial No. 260,216.

In certain types of automotive equipment a spare wheel is held upon a member attached to the chassis by means of cap nuts screwed upon threaded studs extending through holes in a disk or flange of the spare wheel. Generally these screw members are three or more in number and nuts are tightened upon all of them by means of a wrench excepting one upon which is placed a cap nut of somewhat different construction. This last mentioned lug may be described as ordinarily a castellated hexagonal nut from the top of which projects a tongue narrower than the nut itself forming shoulders, and the tongue is perforated to accommodate a locking element.

In the construction of some cars, special locking means must be taken to hold this lug in place. An ordinary padlock snapped through a hole therein will not prevent a theft because the padlock may be turned with the lug by one endeavoring to unscrew it. Thus, in order to provide a safe fastening a cable or chain lock must be used with this lug or a type of lock, which cooperating with some other part of the car or spare wheel construction, will prevent the turning of the lug.

It is an object of my invention to provide a lock of this character which when placed upon the lug will prevent the removal thereof. It is a further object of my invention to provide a small and neat lock for said purpose and one which cooperates with the lug itself so as to maintain a fixed relation thereto, all of which enables me to prevent turning of the lug by a lock of considerably smaller size than would otherwise be necessary to reach and cooperate with the parts of the spare wheel under all conditions.

The above and other objects to which reference will be made in the ensuing disclosure, I accomplish by that certain combination and arrangement of parts of which I have illustrated a preferred embodiment.

In the drawings:

Figure 1 is a section of the spare wheel and holder of a car showing the manner of use of my lock.

Figure 2 is a sectional view through my lock.

Figure 3 is an elevation of the lock swivel part.

Figure 4 is a side view thereof.

Figures 5, 6 and 7 are views of the body part of the lock.

Figure 8 shows my lock in place with a device for preventing the removal of the tire from the rim.

Figure 9 is another elevation of this device in place.

Referring to Figure 1 it will be seen that in the car there is a member 1 attached to the chassis and having a flange 2 in which is mounted screw members 3—3. The spare wheel consists of a hub member 4 to which is attached a flange 5. From the flange to the rim 6 radiate wire spokes 7. The flange 5 is perforated by holes which fit over the bolt members 3 and when the spare wheel has been placed in position nuts 8 are screwed tightly upon these bolts. One of these bolts, however, carries a locking lug consisting of a nut portion 9 and a tongue 10. This construction forms a shoulder 11. The tongue portion 10 is perforated as at 12 to accommodate a locking device. Figure 1 shows my lock 13 in place.

As has been explained above, an ordinary padlock snapped through the holes 12 may not secure the spare wheel. Such a padlock, unless it be of ungainly size, can simply be swung out along the axis of the bolt 3 and can be used by a thief as a means of turning the lock screw 9 so as to unscrew it. With my lock, however, there is maintained a fixed relationship with the lug 9 so that the lock projects therefrom fixedly at right angles to its axis and the length of the lock 13 is such that it will stop against the hub 4 and prevent rotation of the lug 9. The lock 13 may also

stop against one or more of the spokes 7. My lock, by being held in fixed relationship to the lug 9 and being of comparatively small size, has a further advantage that it may be made noiseless particularly in connection with the loop hereinafter referred to, and will not produce a rattle when the car is being driven as so many locking devices do, and as an ordinary padlock snapped through the hole 12 would.

I will now describe the construction of my lock. It consists of a member 14 shown in Figures 5, 6 and 7. This member consists of a round body portion 15 in Figures 6 and 7, from which there extends a narrow tongue 16. This tongue has a plain face 17 which is adapted to lie along one face of the lug 10 and upon this face 17 there is mounted a cylindrical lug 18 which passes through the hole 10. Referring to Figure 7 it will be seen that the sides of the tongue 16 which I have designated as 19 are also plain and these coat with the shoulder 11 upon the locking lug so that when the member 18 is inserted in the hole 10 my lock can not be turned about it as a pivot, but will be held in fixed relationship to the lug nut 9. Within the body 15 is this member I provide a cylindrical hole 20 with a channel 21 intermediate its ends. I also provide a small eccentric cylindrical hole 22 extending from the bottom of the hole 20 down further into the body of the lock. The other part of my lock, as will be understood from Figure 4, comprises a body member 23 provided with a cylindrical tongue 24 adapted to fit closely within the cylindrical orifice 20 so that the member 23 may be swung thereabout. It will now be seen that when the parts of the lock are assembled, and the lug 18 placed within the hole of the locking lug 9, that the member 23 may be swung about its axis so as to bring a complementary tongue thereon, which I have designated as 25, along the line of the tongue 16 and overlie the lug 18, whereupon the lock will be held fixedly on the lug 19. The arrangement of these parts in the locking position is clearly shown in Figure 2. I also provide in the member 23 an eccentric hole 26, which, in the locked position, will lie along the axis of the hole 20, in the member 14. It will now be clear that if a solid member were pushed down the hole 26 and into the hole 22 that the various parts of my lock would be assembled in a fixed relationship, and if so assembled upon the locking lug 9, could not be removed therefrom.

My locking device is preferably of the type comprising concentric tubes lying within the holes 22 and 26, and having a line of cleavage therebetween so that when it is desired to open the lock a key may be caused to make this line of cleavage coincide with the bottom of the cylindrical hole 20 and the top of the cylindrical tongue 24 thereby permitting the

parts 14 and 23 to be rotated with respect to each other. My preferred type of lock is described in my Patent No. 1,390,222, issued September 6, 1921, and I have represented it diagrammatically in Figure 2 as consisting of concentric tubes 27 and 28 controlled by springs 29 and 30. These tubes comprise a line of cleavage which I have designated at 31; and it will be seen in Figure 2 that when a key of the proper shape is inserted in the orifice 32 so as to bear against the concentric tubes 27 and 28, these may be depressed until the line of cleavage permits the rotation of the parts of the lock with respect to each other, and it will be further clear that when the key is withdrawn from the orifice 32, the action of the springs will be to push the cylindrical device out until the solid portions thereof hold the parts of the lock against rotation by means of fixing the eccentric holes 22 and 26 against relative movement. It will be understood that the orifice 32 is closed at the end by a member 32^a for the purpose of preventing the removal of tubes 27 and 28 from the eccentric cylindrical holes and that member will have a slot therein to permit passage of the key. I prefer to make the lock part 23 including this member all in one piece. In assembling my lock I provide a hole 33 as shown in Figures 6 and 7 leading to the channel 21, in the member 14, and I provide in the tongue portion of the member 23 a complementary channel 34 of such size and shape that when the tongue 24 is inserted within the hole 20 it will cooperate with the channel 21 in forming a single circular channel preferably of rectangular cross section. Having assembled my lock in position I drive through the hole 33 and around the circular channel, a malleable metallic bar 35 (Figure 2), which will hold the parts together, and I cut off this bar flush with the surface of the member 14 so that it can not thereafter be withdrawn.

In using my lock I insert a key into the orifice 32, so as to enable me to swing the member 23 relatively to 24 whereupon the tongue 25 is moved aside so as to uncover the lug 18 on the tongue 16. This lug is then inserted in the hole 12 through the locking lug 10, the tongue 25 is swung back into position, the tubes 27 and 28 will be pushed outwardly into the eccentric orifice 26 and lugs 16 and 25 will be held in fixed alignment so that without the use of the key the lock cannot be moved from the locking lug 9. Further the tongues will impinge against the shoulders 11 thereon, and the lock cannot be rotated upon the bolt 12 as a pivot. An attempt with the lock in position to unscrew the lug 9 will result in the lock 13 striking the hub 4 thus preventing the rotation of the lug 9.

I have described my lock as embodying concentric tubes, but it will be understood that

other locking mechanisms may, if desired, be used to prevent relative rotation of the members 14 and 23.

The operation of my lock in preventing the removal of the spare wheels of automotive equipment has been described; but it will be seen that the tire itself is not protected, but can be taken off the rim by a thief. Various means may be taken to prevent this, as by 10 the use of a separate lock and chain. I prefer, however, to use a device shown in Figures 8 and 9. This is a loop of hardened steel wire with a tire-enclosing bend 34, legs 35, and integral eyes 36, upon the ends of these legs. 15 This wire loop is shaped so that, when the legs are sprung apart and the bend placed over the tire, the eyes may be placed around the lug 9. The lock 13 will hold these eyes on the lug, and the spare tire will be effectively 20 locked in place. The loop, being of hardened steel cannot easily be cut or broken, and it forms an effective locking device which may be sold with the lock, which is attractive in appearance when in use, and which will not 25 rattle.

Having thus described my invention, what I claim as new and desire to secure by Letters Patent, is:—

1. A lock mechanism comprising a body 30 having two parts rotatable relative to each other, tongues on each of said parts having plane sides and plane interspaced faces, and a lug upon the face of one of said tongues approaching the face of the other tongue 35 adapted to be uncovered by movement thereof, and locking means to prevent the relative movement of said parts.

2. A lock mechanism comprising a body 40 having two parts rotatable relative to each other, tongues on each of said parts having plane sides and plane interspaced faces, and a lug upon the face of one of said tongues approaching the face of the other tongue and 45 adapted to be uncovered by the movement thereof, and locking means to prevent the relative rotation of said parts, said means comprising an eccentric cylindrical bore and means in said bore comprising elements with a line of cleavage therethrough, said elements 50 adapted to be moved by means of a key until said line of cleavage will permit the rotation of said locking parts.

3. A lock mechanism comprising a body 55 having two parts rotatable relative to each other, tongues on each of said parts having plane sides and plane interspaced faces, and a lug upon the face of one of said tongues approaching the face of the other tongue adapted to be uncovered by the movement thereof, 60 and locking means to prevent the relative rotation of said parts, said locking means comprising an eccentric cylindrical bore and at least one tube therein, said tube having a line 65 of cleavage adapted to permit in one position the relative rotation of the locking parts,

said tube being controlled by a spring so that when said concentric bore is in alignment said tube will be pushed into a position to lock said lock parts against relative rotation.

4. In combination, a lug comprising a nut 70 portion, a perforated tongue thereon, shoulders between said tongue and said nut, and a lock comprising a body in two parts rotatable relatively to each other, each of said parts comprising a tongue with plane sides and a 75 plane face and a circular lug upon the face of one of said tongues and approaching the face of the other tongue, locking means to prevent a relative rotation of said lock parts, the said circular lug mounted upon the said tongue passing through a hole in the tongue of the locking lug, the said plane sides of said tongue cooperating with the shoulders on said locking lug to prevent rotation of said lock around said hole as a pivot, said tongues 80 in alignment whereby the said faces thereof will prevent the removal of said lock from said locking lug, means to hold the parts of said lock against relative rotation, said lock extending perpendicular to the axis of said 85 locking lug to cooperate with a member attached to the screw upon which said lock is mounted to prevent rotation of said locking lug.

5. In combination, a bolt, a locking lug on 90 said bolt comprising a nut, a perforated tongue on said nut, said tongue having plane sides, shoulders between said tongue and said nut, and a lug comprising a body portion in 95 two parts rotatable relative to each other, 100 tongues on said parts, said tongues comprising plane sides and interspaced and parallel plane faces adapted to lie along the plane sides of the tongue upon said locking lug, a lug upon one of said tongues adapted to lie 105 within the hole upon said locking lug, the plane faces of said tongues extending beyond said circular lug and adapted to cooperate 110 with said shoulders so that when said lock is in position it will be fixedly held at right angles to the axis of said locking lug, and means to prevent the relative rotation of said lock parts.

6. A lock mechanism comprising a body 115 having two parts rotatable relative to each other, tongues interspaced and shaped to embrace a member to be locked on each of said parts, and a lug upon the face of one of said tongues approaching the face of the other tongue adapted to enter a hole in said member 120 to be locked, and adapted to be uncovered by a movement thereof, and locking means to prevent the relative movement of said parts.

7. A lock mechanism comprising a body 125 having two parts rotatable relative to each other, tongues interspaced and shaped to embrace a member to be locked on each of said parts, and a lug upon the face of one of said tongues approaching the face of the other tongue adapted to enter a hole in said mem- 130

ber to be locked, and adapted to be uncovered by a movement thereof, and locking means to prevent the relative movement of said parts, said locking means comprising an eccentric cylindrical bore and at least one tube therein,
5 said tube having a line of cleavage adapted to permit in one position the relative rotation of the locking parts, said tube being controlled by a spring so that when said concentric bore is in alignment said tube will be
10 pushed into a position to lock said lock parts against relative rotation.
